(57) **CLAIM**

We claim the ornamental design for a water flosser base unit with reservoir lid, substantially as shown and described.

DESCRIPTION

FIG. 1 is a front, left isometric view of a water flosser base unit with reservoir lid.

FIG. 2 is a rear isometric view of the water flosser base unit with reservoir lid of FIG. 1.

FIG. 3 is a front elevation view of the water flosser base unit with reservoir lid of FIG. 1.

FIG. 4 is a rear elevation view of the water flosser base unit with reservoir lid of FIG. 1.

FIG. 5 is a right side elevation view of the water flosser base unit with reservoir lid of FIG. 1.

FIG. 6 is a left side elevation view of the water flosser base unit with reservoir lid of FIG. 1.

FIG. 7 is a top plan view of the water flosser base unit with reservoir lid of FIG. 1; and,

FIG. 8 is a bottom plan view of the water flosser base unit with reservoir lid of FIG. 1.

The broken lines showing of portions of the article illustrate subject matter excluded from the claim with the broken lines and the areas within forming no part of the claimed design.
